MACHINE PICK SHARPENER

Vay Fisher Neal, Punxsutawney, Pa.

Application July 9, 1943, Serial No. 494,044

4 Claims. (Cl. 51—241)

This invention relates to new and useful improvements in sharpeners for coal mining machine picks and has for its primary object to provide, in a manner as hereinafter set forth, novel means for expeditiously sharpening such picks without the necessity of removing them from the machine.

Other objects of the invention are to provide a coal mining machine pick sharpener of the character described which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view of a machine pick sharpener constructed in accordance with the present invention, showing the device in use.

Figure 2 is a view in side elevation of the device.

Figure 3 is a vertical sectional view, taken substantially on the line 3—3 of Figure 1.

Figure 4 is a view in horizontal section, taken substantially on the line 4—4 of Figure 2.

Figure 5 is a view in vertical section through one of the grinding stones, taken substantially on the line 5—5 of Figure 4.

Referring now to the drawings in detail, it will be seen that the embodiment of the invention which has been illustrated comprises a frame structure which is designated generally by reference numeral 1. The frame 1 comprises a pair of bars 2 having converging rear end portions 3. Fixed on the end portions 3 of the bars 2 is the handle 4. The bars 2 further include angularly or horizontally extending forward end portions 5 which are adapted to rest on the usual upper cutter guide bar 6 of a conventional coal mining machine. An endless chain 7 is operable in the usual manner between the upper guide 6 and a lower guide 8. Brackets 9 are mounted on the chain 7 at spaced points and project at different angles therefrom. The picks 10 are mounted in the brackets 9.

Suspended from the bars 2 at an intermediate point is a substantially segmental housing 11. In the embodiment shown, the housing 11 includes spaced, arcuate, concentric front and rear plates 12 and 13, respectively, top and bottom

plates 14 and 15, respectively, and side plates 16 having openings 17 therein.

Slidably mounted in radial openings which are provided therefor in the inner plate 12 is a plurality of flat grinding stones 18. As illustrated to advantage in Fig. 1 of the drawings, also in the Fig. 4, the grinding stones 18 are mounted diagonally relative to the mining machine chain 7 and in pairs. The construction of the frame 1 is such that the bars 2, which parallel each other, extend at an obtuse angle from the guide 6 of the machine when said frame is engaged thereon. The pairs of grinding stones 18 are so arranged that the adjacent ends thereof are stepped.

15 Thumb screws 19 are threaded for adjustment in the back plate 13 of the housing 11. Coil springs 20 have one end engaged with the screws 19 and their other ends engaged in channels 21 in the rear ends of the grinding stones 18 for yieldingly resisting rearward sliding movement of said stones. The forward ends of the stones 18 have formed therein substantially V-shaped grooves 22 for the reception of the picks 10. Lock nuts 23 secure the screws 19 in adjusted position.

20 It is thought that the operation of the device will be readily apparent from a consideration of the foregoing. Briefly, the end portions 5 of the frame structure 1 are engaged on top of the guide 6 of the machine in a manner to dispose 25 the grooved forward ends of the pairs of grinding stones 18 in the paths of the picks 10. The chain 7 of the machine is reversed in order that the bits 24 of the picks 10 will drag or trail across the stones 18. This is indicated by the arrows 30 in Fig. 1 of the drawings. As the picks 10 are moved across the forward ends of the diagonally mounted pairs of stones 18, said stones are forced rearwardly against the tension of the coil springs 20. Thus sufficient friction is had to sharpen the 35 bits 24 of the picks 10, said bits travelling in the grooves 22. The adjustable thumb screws 19 permit the resistance of the coil springs 20 to be regulated as desired.

40 It is believed that the many advantages of a sharpener constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

45 What is claimed is:

1. A sharpener for the picks of the horizontal 50 endless cutter chain of a coal mining machine,

wherein the cutter chain travels between upper and lower guides, and wherein the picks project from the chain at different angles, comprising, a frame structure engageable with the upper cutter chain guide to hold the sharpener in operative position on the machine, a housing mounted on the frame structure, a plurality of grinding stones arranged in a vertical arc and slidably mounted in the housing and projecting therefrom for engagement by the picks, and means for yieldingly resisting sliding movement of the stones away from the picks when said picks are engaged therewith.

2. A sharpener for the picks of the horizontal endless cutter chain of a coal mining machine, wherein the cutter chain travels between upper and lower guides, and wherein the picks project from the chain at different angles, comprising, a frame structure engageable with the upper cutter chain guide to hold the sharpener in operative position on the machine, a housing mounted on the frame structure, and a plurality of pairs of grinding stones arranged in a vertical arc and slidably mounted in the housing and projecting therefrom for engagement by the picks, and means for yieldingly resisting sliding movement of the stones away from the picks when said picks are engaged therewith, said means including coil springs engaged with the stones, and an arcuate series of thumb screws threaded for adjustment in the housing and engaged with said coil springs.

3. A sharpener for the picks of coal mining machines comprising, a frame including a pair

5 of bars engageable, at one end, on the machine, a handle on the other ends of said bars, a substantially segmental housing mounted on the bars and depending therefrom, pairs of grinding stones mounted radially and slidably in the housing, said stones projecting forwardly from the housing for engagement and rearward actuation by the picks, thumb screws threadedly mounted for adjustment in the housing, and coil springs engaged with said thumb screws and with the stones for yieldingly resisting rearward actuation of said stones by the picks.

4. A sharpener for mining machine picks comprising, a frame structure including a pair of bars engageable, at one end, on a mining machine, a handle on the other ends of the bars, a substantially segmental housing secured beneath the bars and depending therefrom, said housing including spaced, concentric front and rear plates, said front plate having radial openings therein, grinding stones slidably mounted in the openings and projecting forwardly from the housing for engagement and rearward actuation by the picks, said grinding stones having grooves in their forward ends for the reception of the picks and further having channels in their rear ends, thumb screws threadedly mounted for adjustment in the rear plate of the housing, and coil springs having one end engaged with the thumb screws and their other ends engaged in the channels for yieldingly resisting rearward sliding movement of the stones.

VAY FISHER NEAL.
